ANIMAL FEEDING BOWL

Marvin A. Goldman, Great Neck, and Jerome N. Goldman, New York, N.Y., assignors to Penn Plax Plastics, Inc., Jamaica, N.Y.

Filed Jan. 6, 1972, Ser. No. 215,707

Term of patent 14 years

Int. Cl. D30—03

U.S. Cl. D30—16

FIG. 1

FIG. 2

FIG. 3

FIG. 4

FIG. 5

FIG. 6

FIG. 1 is a perspective view of an animal feeding bowl, showing our new design;

FIG. 2 is a top plan view;

FIG. 3 is a front elevational view, the rear being substantially a mirror image thereof;

FIG. 4 is a bottom plan view;

FIG. 5 is a side elevational view, the opposite side being substantially a mirror image thereof; and

FIG. 6 is a cross-sectional view thereof, taken on line 6—6 in FIG. 2.

We claim:

The ornamental design for an animal feeding bowl, substantially as shown and described.
